UNITED STATES PATENT OFFICE.

MELVIN BANCROFT, OF WHITESBOROUGH, NEW YORK, ASSIGNOR TO THE QUIGLEY FURNITURE COMPANY, OF SAME PLACE.

TYPE-WRITER CABINET.

SPECIFICATION forming part of Letters Patent No. 427,216, dated May 6, 1890.

Application filed May 9, 1889. Serial No. 310,125. (No model.)

To all whom it may concern:

Be it known that I, MELVIN BANCROFT, of Whitesborough, in the county of Oneida and State of New York, have invented certain new and useful Improvements in Type-Writer Cabinets; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

My invention relates to an improvement in type-writer cabinets.

In the drawings, Figure 1 shows a front view of the case open, mechanism being shown mounted upon the platform. Fig. 2 shows a section of the case on line A B of Fig. 1. Fig. 3 shows a section on line A B, the mechanism mounted upon the platform being inclosed within the case. Figs. 4 and 4^a show details of construction.

Similar letters and figures of reference refer to like parts in the several figures.

Reference being had to the drawings, 1 indicates the outer walls of the case.

2 2 are partition-walls, although they might be outer walls, the parts of the case on the outside of the same being omitted.

3 are brackets, upon which is mounted movable platform 4. Brackets 3 are provided with inclined face 5, with which pivot 6 engages. Pivot 6 is provided with an anti-friction roller and is secured upon the walls of the case. Stops 7 and 8 upon the case are adapted to come in contact with the platform and prevent movement or displacement thereof, as hereinafter shown. A stop 14 is also provided

40 adapted to engage the platform on the under side and in recess a and secure it in position. A shelf-stop 9 is provided, upon which the inner end of the platform rests when the platform is inclosed. The case is also provided

45 with a cover, hinged at 11 to the case, the cover being composed of the sections 10 and 13, being hinged together at 12, so as to turn inwardly, as shown. A projection 15 upon the case supports the section 10, and 15^a the section 13 of the lid or cover in alignment with the top of the case.

Having thus described the several parts of the case, the operation of the device is substantially as follows: The platform being in the position shown in Fig. 3, and it being desired to expose the mechanism mounted upon the platform, the lid is raised into the position shown in dotted lines. The platform is then drawn forward, the pivot 6 supporting the same, the inclined face 5 of the bracket 3 moving thereon. After the platform has been drawn forward the required distance it is engaged with projecting stop 14 in recess a of the platform 4. After the platform is in position the lid may be again closed, the part 13 being placed behind the rear end of the platform, as shown in Fig. 2, which entirely closes the top of the case when the mechanism is exposed. The bracket and platform, wedging between pivot 6 and stop 7, prevent the platform from being drawn forward so far as to disengage the pivot 6 from the bracket. This stop 7 also prevents the platform from being tilted up by a surplus of weight on the forward end of the platform. When it is desired to close the platform and the mechanism mounted thereon in the case, the lid is raised from the position shown in Fig. 2, so as to clear the mechanism mounted upon the platform. The forward end of the platform is then slightly raised, so as to disengage the recess a from the pin 14, and the platform may then be allowed to run backward and turn downward into the case until it comes in contact with stop 9, and is held thereby. After the platform has been disengaged from stop 14 it will retreat into the case automatically. The stop 8 is provided, adapted to engage the upper surface of the platform, so that when the greater part of the weight has passed back of pivot 6 the platform will not tilt up so far as to miss stop 9. It is evident that stop 9 might be omitted and still furnish a complete mechanism; but I prefer to provide it, as the mechanism is thus entirely inclosed when the case is closed.

What I claim as new, and desire to secure by Letters Patent, is—

1. The combination, in a type-writer cabinet, of the walls of the case, the pivots on the walls, the platform running and turning on the pivots, the projection 14 on the walls

adapted to engage and support the platform in its forward position, the shelf-stop adapted to engage and support the inner end of the platform when inclosed, and the projection 8 on the walls adapted to engage the platform on the top and guide the same in its inward movement.

2. The combination, in a type-writer cabinet, of the walls of the case, a pivot secured to the walls, a platform having inclined ways or faces at an acute angle to the platform running on the pivot, and a projection on the walls for engaging and supporting the platform, substantially as set forth.

15 3. The combination, in a type-writer cabinet, of the walls, pivots on the walls, the platform having inclined faces or ways at an angle to the platform running and turning on the pivots, the projections in front of the pivot adapted to support the platform, and the sectional hinged cover.

4. The combination, in a type-writer cabinet, of the walls, pivots secured to the walls, a platform supported by brackets having inclined faces running and turning on the pivotal points, the projections on the walls in front of the pivotal points adapted to support the platform, substantially as set forth.

25 5. The combination, in a type-writer cab-

inet, of the walls, the pivots secured to the walls, the platform sliding on and tilting over the pivots, the projections 14 in front of the pivots and adapted to engage and support the platform in its forward position, the projection 8 on the walls of the case adapted to engage the platform on top and guide it in its inward movement, the shelf-stop adapted to support the inner end of the platform when inclosed, and the projection 7 on the walls of the case adapted to engage the platform on its upper surface and prevent it tilting over projection 14 when in its normal position.

6. The combination, in a type-writer cabinet, of the walls, the pivots on the walls, the platform mounted on brackets having inclined faces sliding on and tilting over the pivots, and the projection on the walls adapted to engage the platform on top and between which projection and the pivots the platform and brackets are adapted to wedge and limit the forward movement of the platform, substantially as set forth.

In witness whereof I have affixed my signature in presence of two witnesses.

MELVIN BANCROFT.
